PIN MIXER

Robert R. Teale, Snyder, N. Y., assignor to National Gypsum Company, Buffalo, N. Y.

Application April 21, 1951, Serial No. 222,170

7 Claims. (Cl. 259—8)

1

This invention relates to mixers and refers particularly to mixers for preparing slurries of cementitious materials.

The principles of the mixer of the present invention may be applied in mixing various materials, but its advantages are particularly evident in preparing slurries for the manufacture of gypsum products, and its construction and operation will accordingly be discussed herein as applied to the mixing of calcined gypsum or stucco and water to form a slurry of gypsum plaster.

The principles of the present invention are particularly adaptable to mixers of the type known in the art as pin mixers wherein the mixer is in the form of a relatively flat cylinder mounted on a vertical axis with the materials moving through the mixer as a combined result of the force of gravity and centrifugal force and discharging near an edge or peripheral portion of the mixer casing. In such mixers it is customary to introduce the calcined gypsum or stucco and the water at different points located somewhat in the vicinity of the center of the mixer, but conventional construction is such that it is usual to have these two feed entrances disposed separately and each located eccentrically of the center of the mixing chamber and eccentrically of the axis of rotation of the mixing rotor.

Ordinarily the shaft of the mixing rotor and its supporting bearings require that the separate entrance orifices for gypsum and water be located at points spaced from the central region of the mixer. This design and construction, while generally conventional in this art, results in certain undesirable unevenness and inequality in mixing results, since the radial path from the point where the gypsum is introduced to the periphery of the mixer is unequal in various directions, the radial path from the point where the water is introduced to the periphery of the mixer in various directions is unequal, and the paths of the two materials are not the same in various directions.

The mixer of the present invention is so arranged and constructed that it is possible to introduce both the calcined gypsum or stucco and the water centrally of the mixer and in such a way that their paths and the lengths of their paths in all radial directions to the periphery of the mixer are entirely uniform. Further, this arrangement results in all of the calcined gypsum or stucco being supplied with water at the same distance from the axis of the mixer and results

2

in all of the calcined gypsum being supplied with absolutely uniform relative quantities of water.

In the embodiment of the invention, which is set forth in detail herein by way of example, this result is effected by introducing the calcined gypsum in an annular flow concentric with the axis of the mixer, the water being introduced centrally within such annulus and by means of a conduit likewise concentric with the axis of the mixer.

Various mechanical modifications of the mixer may be made without departing from the principles of the present invention. A single specific embodiment is illustrated in the drawings and described herein merely by way of example but the present invention is limited thereto or otherwise excepting as defined in the appended claims.

In the drawings:

20 Fig. 1 is a top plan view, partly in cross-section, of one form of the mixer of the present invention; and

25 Fig. 2 is a longitudinal cross-sectional view on a somewhat larger scale and taken on the line II—II of Fig. 1.

Like characters of reference denote like parts, and the numeral 10 designates generally a flat cylindrical casing having a radial bottom wall 11 and a circular side wall 12. A cover element 13 completes the casing and is provided with a number of concentric circular series of stationary depending pins 14.

30 The mixing rotor comprises generally a flat disc 15 having a mounting shaft portion 16 which may pass through a stuffing box or packing arrangement 17 in the radial bottom wall 11 of casing element 10, although there is necessity for a packed joint or a tight fit at the point where the rotor shaft 16 passes downwardly through bottom wall 11 of the casing. The manner in which the shaft 16 is mounted for driving rotation and the manner in which it is driven form no part of the novel structure of the present invention and accordingly need not be illustrated or described.

35 Rotor 15 is likewise provided with a number of concentric circular series of pins 18 which are disposed at such radii as not to interfere with the stationary pins 14 but which extend upwardly between the circular rows of pins 14 as appears clearly in Fig. 2.

40 The cover member 13 of the mixing chamber is provided with a central conduit 20 for introducing a downward flow of dry calcined gypsum or stucco. A water conduit 21 is fixed to conduit

20 in any desired manner, and its terminal portion extends downwardly centrally of the mixer and centrally of conduit 20 as at 22 in Fig. 2. The terminal portion 22 of water conduit 21 preferably extends down to a point fairly close to the top surface of rotor 15, so that water is forced therefrom uniformly in all radial directions.

A separating sleeve 25 which is likewise coaxial with the conduit 20 and with the axis of rotor 15 is mounted fixedly on a plate 26, which, in turn, is secured to rotor 15 as by means of a plurality of studs 27. A cap 28 extends over the upper end of sleeve 25 and in the illustrated instance is fixed to the downwardly extending portion 22 of the water inlet conduit.

Cap 28 is provided with an annular depending flange which extends downwardly over the upper end of sleeve 25, so that cap 28 and sleeve 25 serve to isolate the flow of calcined gypsum or stucco and the flow of water until the water passes beneath plate 26 and reaches the innermost circular series of the mixing pins. However, cap 28 and sleeve 25 are out of contact so that free rotation of sleeve 25 relative to the cap is not interfered with.

Preferably an upstanding circular series of pins 30 is carried by plate 28 and extends upwardly in the space between sleeve 25 and gypsum conduit 20, the pins serving to keep the incoming calcined gypsum or stucco in a loose and clear flowing condition.

The flow of mixing water and gypsum from the center of the mixer toward the periphery is thus entirely uniform in various directions about the mixer both as to quantity and proportions and the rate of flow is substantially uniform because of these equal values and the uniform centrifugal force on the materials. The material, after passing radially beyond the various intermeshing mixing pins 14 and 18, may be discharged in any desirable manner and at any number of points around the periphery of the mixer. In the present instance, and by way of example only, a discharge spout is designated 31 in Figs. 1 and 2.

In the foregoing specification and the following claims the terms "pin mixer" and "mixing pins" are employed and the pins 14 and 18 are shown as being of circular cross-section. However, it is to be understood that the term "pin" is used in a generic sense, and that the pins or bars may be of square or rectangular cross-section or otherwise, that various combinations of pins and bars may be employed, and that the claims are to be construed in that light.

What is claimed is:

1. In a pin mixer, a generally cylindrical casing having a vertical axis and radially extending top and bottom walls, a plurality of stationary mixing pins projecting downwardly from the top wall of said casing, a discoidal rotor in said casing having a plurality of upwardly projecting mixing pins, located so as to pass between the stationary mixing pins upon rotation of said rotor, rotary drive means at the under side of said rotor, an inlet conduit communicating with said mixer concentrically through said top wall, and a second conduit extending within said first conduit centrally thereof and downwardly in said mixer substantially below the lower end of the first conduit, sleeve means carried by said rotor with its lower end adjacent to the lower end of said second conduit and extending upwardly between said conduits concentrically and spaced radially from both con-

duits, and a concentric cap carried by said second conduit and extending over the upper end of said sleeve means, whereby said cap and said sleeve means insure isolation of the materials of the two conduits until they merge in the mixing chamber.

2. In a pin mixer, a generally cylindrical casing having a vertical axis and radially extending top and bottom walls, a plurality of stationary mixing pins projecting downwardly from the top wall of said casing, a discoidal rotor in said casing having a plurality of upwardly projecting mixing pins, located so as to pass between the stationary mixing pins upon rotation of said rotor, 10 rotary drive means at the under side of said rotor, an inlet conduit communicating with said mixer concentrically through said top wall, and a second conduit extending within said first conduit centrally thereof and downwardly into said 15 mixer whereby both conduits discharge material uniformly coaxially in said chamber, sleeve means carried by said rotor with its lower end adjacent to the lower end of said second conduit and extending upwardly between said conduits 20 concentrically and spaced radially from both conduits, and a concentric cap carried by said second conduit and extending over the upper end of said sleeve means, whereby said cap and said sleeve means insure isolation of the materials 25 of the two conduits until they merge in the mixing chamber.

3. In a mixing device, a casing forming an annular mixing chamber, a discoidal rotor therein having a substantially vertical axis, rotary drive means at the under side of said rotor, an inlet conduit disposed above said casing and communicating with said mixing chamber centrally thereof through the upper wall of said chamber, and a second inlet conduit extending downwardly into said mixing chamber within said first conduit and centrally thereof, said second conduit extending downwardly in said casing substantially beyond the lower end of said first conduit, sleeve means carried by said rotor with its lower end adjacent to the lower end of said second conduit and extending upwardly between said conduits concentrically and spaced radially from both conduits, and a concentric cap carried by said second conduit and extending over the upper end of said sleeve means, whereby said cap and said sleeve means insure isolation of the materials of the two conduits until they merge in the mixing chamber.

4. In a mixing device, a casing forming an annular mixing chamber, a discoidal rotor therein having a substantially vertical axis, rotary drive means at the under side of said rotor, an inlet conduit disposed above said casing and communicating with said mixing chamber centrally thereof through the upper wall of said chamber, and a second inlet conduit extending downwardly into said mixing chamber within said first conduit and centrally thereof, whereby both conduits discharge material uniformly coaxially in said chamber, sleeve means carried by said rotor with its lower end adjacent to the lower end of said second conduit and extending upwardly between said conduits concentrically and spaced radially from both conduits, and a concentric cap carried by said second conduit and extending over the upper end of said sleeve means, whereby said cap and said sleeve means insure isolation of the materials of the two conduits until they merge in the mixing chamber.

5. In a mixing device, a casing forming an an-

nular mixing chamber, a discoidal rotor therein having a substantially vertical axis, rotary drive means at the under side of said rotor, an inlet conduit disposed above said casing and communicating with said mixing chamber centrally thereof through the upper wall of said chamber, and a second inlet conduit extending downwardly into said mixing chamber within said first conduit and centrally thereof, whereby both conduits discharge material uniformly coaxially in said chamber, an annular plate extending about said second conduit and underlying the discharge portion of the first conduit, whereby material feeding into the mixing chamber from said first conduit moves radially outwardly above said annular plate and the material feeding into the mixing chamber from said second conduit moves radially outwardly below said plate and the two materials commingle only after passing radially outwardly beyond said plate.

6. In a mixing device, an annular mixing chamber, a discoidal rotor in said chamber, a drive shaft for said rotor fixed concentrically thereto and extending downwardly out of said chamber and a pair of coaxial conduits of different diameter communicating with the upper wall of said chamber concentrically thereof for introducing a plurality of ingredients by coaxial concentric downward flow, an annular plate surrounding the lower end of the inner of said conduits and spaced below the lower end of the outer of said conduits whereby material feeding into the mixing chamber through the inner conduit moves radially outwardly beneath said annular plate and material feeding into the mixing chamber through the outer of said conduits moves radially outwardly above said annular plate and

the respective materials commingle only after passing radially outwardly beyond said plate.

7. In a mixing device, a casing forming an annular mixing chamber, a discoidal rotor therein having a substantially vertical axis, rotary drive means at the under side of said rotor, an inlet conduit disposed above said casing and communicating with said mixing chamber centrally thereof through the upper wall of said chamber, and a second inlet conduit extending downwardly into said mixing chamber within said first conduit and centrally thereof, whereby both conduits discharge material uniformly coaxially in said chamber, means extending about said second conduit and including an annular plate underlying the discharge portion of the first conduit, whereby material feeding into the mixing chamber from said first conduit moves radially outwardly above said annular plate and material feeding into the mixing chamber from said second conduit moves radially outwardly below said plate and the two materials commingle only after passing radially outwardly beyond said plate.
